HENRY THOMPSON, OF ROCKLAND, MAINE.

Letters Patent No. 65,450, dated June 4, 1867.

IMPROVED WINDLASS FOR VESSELS.

The Schedule referred to in these Letters Patent and making part of the same.

TO ALL PERSONS TO WHOM THESE PRESENTS SHALL COME:

Be it known that I, HENRY THOMPSON, of Rockland, in the county of Knox, and State of Maine, have made a new and useful invention, having reference to the Windlass of a Navigable Vessel; and I do hereby declare the same to be fully described in the following specification, and represented in the accompanying drawings, of which—

Figure 1 is a top view of a windlass provided with my invention.

Figure 2 is a front elevation, and

Figure 3 a side elevation of my mechanism, which is applied to the windlass to prevent fleeting of its chain cable, or the riding of one coil while being formed upon the next one, a matter which it is very desirable to avoid, as is well understood by mariners, serious consequences being liable to result from such an accident or occurrence.

In the drawings, A denotes an ordinary windlass, supported on bits B B, and provided not only with mechanism for revolving it, but with a ratchet, a, and a pawl, b, for preventing it from turning backward under the draught on the cable H. This mechanism is of a kind well known and in common use, it consisting of two ratchets, each of which is fixed to the windlass, and enclosed in one of two pawl-cases C C, which embrace and turn on the windlass, and carry pawls to act on the ratchets. These pawl-cases are connected by rods to a brake or lever, D, which, on being vibrated on its fulerum, will impart a reciprocating motion to each pawl-case, one being moved in one direction while the other is in the act of being moved in the opposite direction. In front of the windlass, and hinged to the deck E, is a standard, F, carrying a roller, e, and being connected with one of the pawl-cases by means of a bar, d. Such bar is to be jointed to the case and standard in such manner as to cause the pawl-case, during its movements, to impart to the standard and its roller vibratory movements, such as will force the ratchet against and away from the next adjacent coil of the cable on the windlass, the object being to crowd the coil aside a little, or to such extent as to prevent the new coil, while being laid, from overriding that so pushed aside. In order to prevent the standard from being pressed away from the windlass there is jointed to the former and the deck a stay-bar, G, (see fig. 3,) which, though connected with the deck, and arranged in manner as represented, moves with the standard.

I make no claim to the mechanism for revolving the windlass, as such as hereinbefore mentioned is well known and in common use. What I do claim as my invention, is—

The arrangement as well as the combination of the vibratory standard F and its roller e, or the equivalent thereof, with the windlass A and one of its pawl-cases C C, so as to be operated by such pawl-case, substantially in the manner and for the purpose as hereinbefore specified.

I also claim the combination and arrangement of the vibratory standard F, its roller e, or the equivalent thereof, the stay G, and the connection-bar d, as described, the whole to be applied to the deck and windlass of a vessel and the pawl-case of such windlass, substantially as and for the purpose hereinbefore explained.
